(57) **CLAIM**

The ornamental design for a watch band adapter system, as substantially shown and described.

DESCRIPTION

FIG. 1 is a perspective view of a watch band adapter of the present invention;

FIG. 2 is a top view of the watch band adapter of the present invention, the bottom view being a mirror image thereof; FIG. 3 is a right side view of the watch band adapter of the present invention, the left side view being a mirror image thereof;

FIG. 4 is a front view of the watch band adapter of the present invention;

FIG. 5 is a rear view of the watch band adapter of the present invention;

FIG. 6 is a top view of a pair of watch band adapters of the present invention installed on a watch;

FIG. 7 is a top view of a pair of watch band adapters of the present invention installed on a watch with a watch band; and,

FIG. 8 is a bottom view of a pair of the watch band adapters of the present invention installed on a watch with a watch band.

The broken line showing details in the Figures is included for the purpose of illustrating environment of the watch band adapter system and forms no part of the claimed design.
